(57) **CLAIM**

I claim the ornamental design for a set of dentures, as shown and described.

DESCRIPTION

FIG. 1 is an upper front perspective view of a set of dentures showing an upper denture.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof; the left side is a mirror image thereof.

FIG. 7 is a close-up view of the encircled material in FIG. 1.

FIG. 8 is a bottom perspective view of a set of dentures showing a lower denture.

FIG. 9 is a bottom plan view thereof.

FIG. 10 is a top plan view thereof.

FIG. 11 is a front elevation view thereof.

FIG. 12 is a rear elevation view thereof; and,

FIG. 13 is a right side elevation view thereof; the left side is a mirror image thereof.

The broken lines shown in the figures are included for the purpose of illustrating portions of the set of dentures and form no part of the claimed design.
